S. E. Thomas

UNITED STATES PATENT OFFICE

HERBERT E. SCHLESINGER, OF YPSILANTI, MICHIGAN

ADJUSTABLE HANGER FOR BEAMS AND JOISTS

Application filed September 18, 1929. Serial No. 393,362.

My invention relates to an adjustable hanger, for joists, beams or like members, used in building construction, as shown in the accompanying drawings, and more particularly described in the following specification and claims.

The invention comprises a combined hanger and beam extension member, which may be easily and quickly secured to the ends of beams or joists,—thereby providing a better connection and facilitating the erection of the beams that a saving of time and material may be effected.

It is well known in the building trade that lumber is marketed in lengths of an even number of feet, and that there is usually a considerable loss through wastage on beams and joists. For example:—if joists 8' 6" are required for a certain building construction, it is necessary to buy 10' 0" lengths and cut them down to 8' 6".

The primary object therefore of the present invention is to provide an adjustable hanger which while providing a better support for joists is also adapted to retain the joists in an upright position without nailing or cross-bridging;—the extensible feature of the hanger permitting the use of joists of various lengths of span. Thus in a span 8' 6", and 8' 0" joist could be used with the present hanger instead of a 10 ft. piece as formerly required, thereby resulting in the saving of 20% in lumber alone.

In temporary building construction, such as centering floors, this device has particular advantages.

In this class of construction, it is necessary to erect and remove the joists as readily and quickly as possible;—the lumber being frequently used again and again on different floors during the erection of a high building. Therefore by the employment of this device, it is possible to use the joists many times over various spans, without cutting or splicing,—resulting in a large saving in time, lumber and material.

A very considerable advantage gained by the use of this invention in the class of construction just referred to, is that the joist may be held in an upright position without

other securing or bracing means, and by its use the ends of the joists are less liable to crack or split, as the member is handled and brought into use again and again throughout the job.

A further object of the invention is to provide a device which is simple and inexpensive to construct and one practically indestructible.

A further object of the invention is to provide a device which is not only adapted for wooden beams or joists, but is equally fit for use with steel beams or other like building material.

With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a perspective view of the hanger attached to the end of a joist;—a fragment of the latter being shown.

Figure 2 is a fragmentary perspective view of the hanger with parts broken away to more clearly disclose its construction;—as viewed from the end opposite that presented in Figure 1.

Figure 3 is a fragmentary side elevation of a joist, the ends of which are secured in hangers resting on the wall of a building.

Figure 4 is a cross-sectional view taken on or about line 4—4 of Figure 1.

Figure 5 is a perspective view of a modification of the hanger showing the fragmentary end of a joist supported thereby.

Figure 6 is a cross-sectional view through the device taken on or about line 6—6 of Figure 5.

Figure 7 is a perspective view of another modification of the hanger, showing the joist supporting members constructed of opposing channel members in place of the angle-iron shown in Figure 1.

Referring now to the letters of reference placed upon the drawings:

A, A are two parallel L-shaped members of suitable length maintained in spaced relation by plates B, B, spot welded to the upper horizontal flanges of said members.

C, C are L-shaped members secured in correspondingly spaced relation by plates D, D, D¹, preferably spot-welded thereto. The members C, however are bent at an angle (C¹) midway of their length, whereby the major portion of the members C are spaced a relatively greater distance from the members A to receive the ends of a joist E, than at the opposite end of the hanger,—which forms a foot portion adapted to rest upon the building wall F.

G, G are bolts located on opposite sides of the joist extending through the horizontal flanges of the members A and C which upon the adjustment of the nuts G¹ draw together the members A and C, thereby securely clamping the joist between the plates B and D.

In the modification shown in Figures 5 and 6, the lower angle members C, C, and their connecting plates D have been dispensed with, and in place of the bolts G, shown in Figure 1, U-shaped bolts I, supported in the horizontal flanges of the upper angle iron A are employed,—with a plate J, located between the joist and the loop of the bolt—see Figures 5 and 6.

To assist in maintaining the vertical walls of the L-shaped members in proper spaced relation, U-shaped clip plates K are welded to the flanges of the L-shaped members—see Figure 5.

In Figure 7 another modification is shown in which opposing channel members L, L are held at one end in spaced relation by bolts M, M, extending through cross strips N, N attached to the channel members and to the brackets O, O, attached to the other member; the flanges of the channel members being preferably welded together, as at L¹ at the opposite end.

P indicates a foot plate welded to the underside of the lower channel member to provide a relatively broad support for the device on the wall of a building.

Having indicated the several parts by reference letters, the construction and method of employing the device will be readily understood.

In use, a beam or joist is inserted between the spaced walls of the hanger and the nuts of the respective bolts G, G or M, M are then adjusted to securely clamp the joists between the cross plates bridging the vertical walls of the spaced members.

The footing D and its equivalent P in the modification (see Figure 7) is designed to rest upon the wall of a building—see Figure 3 of the drawings.

Joists of greater or lesser length may be

inserted in the hangers, the latter being adjusted in relation to the ends of the joists to provide a beam of the required longitudinal length;—the nuts are then tightened, securing the joists in the hangers.

To admit of nailing a floor or other horizontal member to the joist, slots Q are provided in the upper supporting member of the hanger for the passage of nails into the joist—see Figure 7.

Having thus described my invention, what I claim is:

1. A structural unit adapted to be adjustably mounted on a joist, whereby the span of the joist may be varied, said structural unit comprising a sleeve-like portion, adapted to receive the joist, and also a bearing portion, affording support above the plane of the lower edge of the joist.

2. A structural unit for supporting transverse loads, comprising a truss-like portion telescopically engaged upon a beam portion, said truss-like portion having top and bottom chord members, adapted to embrace said beam portion; and means for securing said truss-like portion and beam portion in relative position.

3. A supporting hanger adapted to be adjustably mounted on the ends of a joist to lengthen the joist to fit spans of varying size;—said hanger comprising upper and lower opposing members spaced apart in parallel relation at one end to receive the ends of the joist,—the opposite end of the lower member extending upwardly in relatively closer relation to the upper opposing member to form a bearing portion for the joist, adapted to rest upon a support, whereby the lower edge of the joist is below the plane of the bearing portion; and means for engaging the upper and lower members of the hanger to draw them toward each other to grip the joist.

4. A structure as specified in claim 3 in combination with a plurality of transverse plates attached to the upper and lower members of the hanger.

5. A structure as specified in claim 3 in combination with a transverse plate attached to the underside of the footing, to provide a relatively broad supporting surface.

6. A joist supporting hanger adapted to be adjustably mounted upon the ends of a joist to lengthen the latter to fit spans of various size; said joist supporting hanger comprising an upper pair and a lower pair of opposing longitudinal members spaced apart laterally to embrace opposite sides of the joist, said upper and lower pairs of opposing members being also spaced apart vertically in parallel relation at one end to receive the ends of a joist, the opposite end portion of the lower pair of longitudinal members being bent toward the upper pair of members adjacent said end portion, the immediate adjacent end

portions being parallel to the upper members to provide a bearing for the joist, adapted to rest upon a support, a plurality of transverse plates attached to, and overlapping respectively the walls of the upper and lower members; and bolts fitted with nuts extending through the walls of the opposing members, whereby upon adjusting the nuts, said members may be drawn toward each other to grip and adjustably secure said hanger to the end of the joist.

7. A supporting hanger adapted to be adjustably mounted on the ends of a joist to lengthen the joist to fit spans of varying size;—said hanger comprising upper and lower opposing members spaced apart at one end to receive the end of the joist;—the opposite end of the lower member extending upwardly in relatively closer relation to the upper opposing member to form a bearing portion for the joist, adapted to rest upon a support, whereby the lower edge of the joist is below the plane of the bearing portion; and means for engaging the upper and lower members of the hanger to grip the joist.

In testimony whereof I sign this specification.

HERBERT E. SCHLESINGER.
